UNITED STATES PATENT OFFICE.

HARRISON G. McFADDIN, OF BROOKLYN, NEW YORK.

DESIGN FOR A GAS AND LAMP GLOBE.

SPECIFICATION forming part of Design No. 15,273, dated August 19, 1884.

Application filed June 17, 1884. Term of patent 7 years.

To all whom it may concern:

Be it known that I, HARRISON G. McFADDIN, of Brooklyn, in the county of Kings and State of New York, have invented and produced a new and original Design for Gas and Lamp Globes, of which the following is a full, clear, and exact description.

Reference is to be had to the accompanying drawing, forming part of this specification, in which the figure is a side elevation of my newly-designed globe.

My design consists in a lamp or gas globe possessing the peculiar configuration herein-after described and claimed.

15 The body A of the globe may be spherical in form, contracted at B, from which point the upper edge of the globe is flared outwardly, as shown at C. The outwardly-flared portion C

is made in large scallops D D, which are set alternately in and out, and these large scallops 20 have the small finger scallops or flutes E E in them, so that the globe presents to the eye the appearance of having a fluted ruffle at its upper edge.

I claim—

25 The design for lamp and gas globes herein described, the same consisting of the body A, presenting the appearance of a sphere contracted at B, and flared outwardly at C, and the large scallops D, and finger-scallops E, at 30 the flaring upper edge of the globe, as shown.

HARRISON G. McFADDIN.
